RAILWAY RAIL CONSTRUCTION

Filed July 9, 1925

2 Sheets-Sheet 2

George W. Muller,
by William D. Gane
his Attorney

UNITED STATES PATENT OFFICE.

GEORGE W. MULLER, OF WASHINGTON, DISTRICT OF COLUMBIA.

RAILWAY-RAIL CONSTRUCTION.

Application filed July 9, 1925. Serial No. 42,540.

To all whom it may concern:

Be it known that I, GEORGE W. MULLER, citizen of the United States, residing at Washington, District of Columbia, have invented certain new and useful Improvements in Railway-Rail Construction, of which the following is a specification.

This invention relates to railway rail construction, and has for one of its objects to provide a rail formed of a plurality of parts including a head portion, and so arranged and connected that the head containing portion may be transposed when worn to present an unworn portion for engagement by the wheels and flanges of the rolling stock.

Another object of the invention is to provide an improved rail formed of a plurality of parts including a compound head portion which is reversible and transposable to enable the portion containing the head when worn to be reversed to present an unworn head portion for engagement by the rolling stock, and also capable of being transposed with the same end in view. By this latter arrangement a rail is produced containing four wearing surfaces.

With these and other objects in view the invention consists in certain novel features of construction as hereinafter shown and described and then specifically pointed out in the claims, and in the drawings illustrative of the preferred embodiment of the invention:

Figure 1 is a side elevation of the confronting portions of a pair of rails constructed in accordance with the invention.

Figure 2 is a plan view of a portion of the parts shown in Figure 1.

Figure 3 is a transverse section on the line 3—3 of Figure 1, looking in the direction of the arrow.

Figures 4, 5 and 6 are views similar to Figure 3, illustrating modifications in the construction.

The improved rail is preferably formed of steel with a lower or base portion including a tie flange 10 and web portions 11, the latter having a slightly beveled upper terminal 12, with the upper portion hardened.

The wearing portion of the rail comprises a head 13 and web 14, the head portion having a longitudinal channel 15 to receive the tapered head 12 of the web 11, as shown.

In the form of the rail illustrated in

Figures 1, 2 and 3, head portions 13 are shown at each edge of the web 14, and each with a longitudinal channel 15, one head portion bearing upon the upper face of the tie flange 10, as shown in Figure 3. The rail portion thus constructed may be reversed to bring either head portion uppermost, and thus present either head for engagement by the rolling stock.

The two head portions may also be transposed from one side to the other of the track, thus being capable of presenting four separate wearing faces, as the main wear upon the rails is upon the confronting portions of the heads, and by transposing the head portions, or changing from one side of the track to the other, each face of each of the head portions may be presented for engagement by the rolling stock, and thus materially increase the life and durability of the rails, thereby insuring a material saving in freight and handling charges.

At the lower edge of each of the head portions 13 at each side, a small longitudinal outstanding bead 16 is formed.

In the form of the structure shown in Figures 1, 2, 3, 4 and 5, a clamp plate 17 is applied to the rails opposite each joint, each plate having a channel at the upper edge to bear over the adjacent bead 16, and bearing at the lower edge upon the upper face of the flange 10.

The web portion 11 is reduced intermediate the edges whereby slight shoulders 18 are formed, and each side of the webs 14 is formed with a longitudinally directed bead 16, one of the beads 16 of the head 13, which for the time being is presented downwardly, and adapted to bear upon the adjacent stop shoulder as shown in Figures 3 and 6, and thus materially assist in supporting the head bearing portion of the rail.

In the structure shown in Figure 3 an additional clamp plate 20 is employed with a channel to bear over the adjacent bead 16, and tapered at the lower edge and engaging thereby in the channel 15 of the head portion 13 which for the time being is presented downwardly.

In Figures 4 and 5 the web 14 is shown formed without the second head portion 13, with the free edge laterally extended and resting on the upper face of the tie flange.

In Figure 4 a single clamp plate 17 is em-

ployed, while in Figure 5 an additional clamp plate 23 is provided, the latter having a longitudinal channel to receive the adjacent bead 16.

5 A clamp bolt 21 of the usual construction operates through the clamp plates 17, 20 and 23, and through the webs 11 and 14, and binds the parts firmly together.

10 Each of the tie flanges 10 rests upon a block 24 of wood, or any other suitable material, while the latter is located on a concrete foundation or support, indicated conventionally at 25.

15 The tie flanges 10 are secured to the blocks 24 and the concrete foundation members 25 by clamp members 26 and clamp bolts 27.

20 The wood blocks 24 serve as cushion elements to receive the concussions, and prevent them from being conducted to the rolling stock.

25 The web 14 is formed with a longitudinally directed recess or cavity opposite the reduced portion of the web 11, and disposed within the cavity is a strip of relatively soft wood indicated at 28, the strip extending the full length of each rail, and operates to deaden the sound and absorbs a large portion of the jars and concussions incident to traffic over the rails; the twang of the rails being entirely eliminated by the use of said strip.

30 The soft wood strip 28 is entirely concealed within the rail structure, and will not be effected by rain or snow and other deteriorating elements and will last indefinitely.

35 By this arrangement the vertical line of strain is directly through the center of the head 13, which for the time being is uppermost, and likewise through the center of the web 11 and tie flange 10, and any tendency to lateral displacement or overturning of the rails is effectually resisted.

40 The coaction between the beads 16, clamp plates 17, 20 and 23 and the shoulders 18, is an important feature, and materially increases the stiffness and deflection resisting quality of the rail.

45 What is claimed and desired to be secured by Letters Patent is:—

50 1. A railway rail, including a tie flange and an up-standing web, the said web comprising a thicker head portion and a thicker lower portion adjoining the said rail flange and an intermediate thinner portion extending between the said thicker portions whereby shoulders are formed on both sides of the rail web at the junction of the said thinner intermediate portion and the said thicker lower portion of the web, a supplementary rail constructed for arrangement on either side of the web and having a groove adapted to engage the said head of the web, said rail having also a bead fashioned and disposed to engage either of the said shoulders on

whichever side of the web the said rail may be placed, and securing means for fastening the said rail and web together.

55 2. A railway rail, including a tie flange and an up-standing web, the said web comprising a thicker head portion and a thicker lower portion adjoining the said tie flange and an intermediate thinner portion extending between the said thicker portions whereby shoulders are formed on both sides of the web at the junction of the said thinner portion and the said thicker lower portion of the web, a reversible rail constructed for arrangement on either side of the said web, the said rail having a head provided with a groove formed to engage the said head portion of the web, the said rail having beads fashioned and disposed to engage the said shoulders of the web on whichever side of the web the said rail may be placed, a clamping plate, and means for fastening the said plate and rail and web together.

60 3. A railway rail, including a tie flange and an up-standing web, the said web comprising a thicker head portion and a thicker lower portion adjoining the said tie flange and an intermediate thinner portion extending between the said thicker portions whereby shoulders are formed on both sides of the web at the junction of the said thinner portion and the said lower thicker portion of the web, a reversible rail constructed for arrangement on either side of the web, the said rail having a head provided with a groove formed to engage the said head portion of the web, the said rail having beads fashioned and disposed to engage the said shoulders of the said web on whichever side of the web the rail may be placed, a clamping plate for securing the rail and constructed to engage the uppermost head of the rail and the said tie flange, and a second clamping plate arranged upon the external side of the rail and constructed to engage one of the beads of the said rail and the groove in the lower head of the rail, and means for fastening said plates and rail and the web together.

65 4. A railway rail including a tie flange and an up-standing web, a head portion having outstanding longitudinally directed beads and a longitudinally directed channel to receive the up-standing web and a depending web portion to bear on the tie flange, a clamp plate bearing against the head portion and against the up-standing web and formed with a longitudinally directed seat to engage over the bead of the head, and means for clamping the parts together.

70 5. A railway rail including a tie flange and an up-standing web, a head portion having outstanding longitudinally directed beads and a longitudinally directed channel to receive the up-standing web and a de-

pending web portion to bear on the tie flange, clamp plates bearing upon opposite sides of the head portion and upon opposite sides of the upstanding web and having 5 longitudinally directed seats to engage over the beads of the head, and means for clamping the parts together.

6. A railway rail, including a tie flange and an upstanding web thereon, a supplemental invertible and reversible rail having 10 heads constructed to be arranged alternately over and upon the top of the said web and in contact with the said tie flange on either side of the said web, and means for securing 15 the rail to the web in either of its positions with respect to the said web and flange.

7. A railway rail including a tie flange and an upstanding web thereon, a supplemental invertible and reversible rail having 20 heads constructed to be arranged alternately into operative position over and upon the top of the said web, each of the said heads of the rail having longitudinal beads on both sides of the heads, and means engaging 25 both of the said beads of the head in operating position for securing the rail to the web in either of its positions with respect to the web.

8. A railway rail, including a tie flange 30 and an up-standing web thereon, a supple-

mentary rail constructed to be placed in operative position on either side of the said web, the said web being also constructed for arrangement into a second operative position on either side of the said web by inverting the rail, the said rail having two load-carrying heads, the said heads having grooves whereby the head of the rail in operating position engages the top of the said web, and means for securing the said rail to the web in either of the positions of the rail.

9. A railway rail, including a tie flange and an up-standing web thereon, a supplemental rail constructed to be placed in 45 operative position on either side of the said web, the said rail being also constructed for arrangement into a second operative position on either side of the said web by inverting the rail, the said rail having two load-carrying heads, the top of the said web being wedge-shaped, the said heads of the rail having grooves fashioned to engage the said wedge-shaped top of the said web whereby the head of the rail in operating 50 position engages the top of the said web, and means for securing the said rail to the web in either of the positions of the rail.

In testimony whereof I affix my signature.
GEORGE W. MULLER.
